UNITED STATES PATENT OFFICE.

CHARLES BRAND OFFICER, OF WINNETKA, ILLINOIS, ASSIGNOR TO SULLIVAN MACHINERY COMPANY, A CORPORATION OF MASSACHUSETTS.

MINING MACHINE.

Application filed December 5, 1917, Serial No. 205,648. Renewed October 10, 1925.

My invention relates to mining machines. It has for its object to provide improved means whereby a mine face may be cut at increased speed and with greater facility. A further object of my invention is to provide improved means whereby a kerf may be cut in the face of an entry in such a manner as to facilitate the shooting and loading of coal, at the same time that the area of the kerf, and the time consumed in cutting the same, is materially reduced. I attain these objects by providing an improved mechanism adapted to be readily transported about the mine to and from the different places to be cut and including improved means whereby the same may cut in an improved manner a vertical or shear cut in the face extending in entry work from substantially the top thereof to the entry bottom and preferably disposed along the center line of the entry.

In the accompanying drawings, I have shown for purposes of illustration two embodiments which my invention may assume in practice.

In these drawings,—

Fig. 1 is a side elevation of one form of my improved machine ready to be adjusted into cutting position in an entry. Fig. 2 is a plan view of the machine shown in Fig. 1, the same also being equipped with an angling jack.

Fig. 3 is a rear elevation of the machine shown in Fig. 1, the feed chain being omitted to facilitate illustration.

Fig. 4 is an elevation of the face of the entry showing the kerfs adapted to be cut therein and the shot holes.

Fig. 5 is a detail view of the double acting jack shown in Fig. 2.

Fig. 6 is a side elevation of a modified form of the machine shown in Fig. 1, the kerf cutting element being shown in position to make its sumping cut.

Fig. 7 is a diagrammatic view of the machine shown in Fig. 1 when the same is in transport position, a vertical section of the entry being shown.

Fig. 8 is a similar view showing the machine ready to begin its sumping cut.

Fig. 9 is a similar view showing the machine at the completion of its starting cut and ready to begin its swinging cut.

Fig. 10 is a similar view showing the machine at the completion of its swinging cut.

Fig. 11 is a similar view showing the machine at the completion of its withdrawal cut.

Fig. 12 is a similar view showing the machine connected in such a manner as to be propelled longitudinally by its feeding element.

In the illustrative disclosure shown in Fig. 1, I have shown a longwall mining machine 1 of standard form (see the patent to Morris P. Holmes, No. 1,544,398, June 30, 1925) including the usual motor driven machine feeding and cutter chain driving mechanism, the machine in my improved construction being mounted edgewise or upon its side in such a manner as to dispose its cutter bar 2 vertically and cause its cutter chain 3 to run in a vertical plane. In a preferred form, this machine is also disposed at such a height as to bring its cutter bar when horizontally disposed substantially opposite the center of the vein.

As shown, the machine is fixed in suitable spaced, upstanding flanges 4 and supported on a rear rotary support or turntable 5 and a front transversely disposed arcuate guiding and supporting member 6, each in turn supported on a truck frame 7. This truck frame is also mounted on wheels 8 adapted to move upon the track 9 and to be driven through suitable driving connections 10 preferably including a clutch mechanism 11, from a shaft 12 in turn operatively connected to and rotatable in either direction at either of two different predetermined speeds with the feed sprocket 13 of the machine. The latter is, as usual, controllable by the motor controlling mechanism including the controller handle 14, the friction controlling mechanism including a friction clutch controlling lever 15, the speed controlling lever 16, and the reverse controlling lever 16a. The driving of the truck from the feeding mechanism of the mining machine is not broadly my invention, but is the invention of one Morris P. Holmes. The bar 2 of this machine is also pivotally connected to the front end of the machine frame and movable about a horizontal pivot 17 thereon, in such a manner that the bar may assume the transport position shown in Fig. 1 or be adjusted about its pivot in a vertical plane to bring its extremity into alignment with either the top or the bottom of the entry, locking means including registering

110

perforations 18 in the frame and bar and a locking pin 19 receivable in said perforations, being provided to maintain the bar in its different positions of adjustment. It will 5 also be observed that means for adjusting the bar about its pivot 17 are provided in the form of a feeding element, herein shown as a flexible element or chain 20 operatively connectable to a fixed part 21 on the bar 2 10 and having its rear end disposable around either idler of a pair of idlers 22 located at opposite corners of the rear end of the frame and also around the adjacent driving sprocket 13, the position of the chain depending 15 upon whether it is desired to raise or lower the bar. As in the usual construction, it will of course be understood that the motor of the mining machine 1 is operatively connected to both the cutter chain 3 and the 20 feed sprocket 13 in the usual manner to provide power to rotate these elements, which are driven from opposite ends of the motor, and that a suitable clutch mechanism including the reverse lever 16^b and the controlling member 23 is provided to control the connection of the chain 3 to the mining 25 machine.

In the operation of my improved machine, the same is preferably driven by its truck driving mechanism and under its own power down the track 9 and into the entry to be extended, the track preferably being so laid that the bar is disposed in the center of the entry. During this transporting operation, 30 the rear end of the feeding element 20 is withdrawn from the sprocket 13, as shown in Fig. 7, to permit the latter to be freely rotated to propel the shaft 12, and the bar 2 preferably occupies the position shown in that figure, the same remaining in that position until the end of the bar has been brought substantially opposite the end of the track and substantially into engagement with the vertical face of the entry to be cut. 35 When this position has been reached, the operator first threads the chain 20 over the upper idler 22 and around the driving sprocket 13 and then, through suitable operation of the usual feed controlling elements, causes the feed sprocket 13 to be rotated in such a manner as to draw in its flexible feeding member 20 and, after the pin 19 has been withdrawn, cause the bar 2 to be swung up until its extremity is disposed substantially in the plane of the top 40 of the entry, i. e. until it occupies the position shown in Fig. 8, which is the position which the parts occupy when the machine is ready to make its starting cut. In a preferred form, the bar is then locked in this position by means of the reinsertion of the pin 19. The sumping cut is then made through operation of the clutch 11, in such a manner as to cause the truck 7 to be propelled along the track 9 until the bar has

been advanced into the coal substantially throughout its length, and until the truck 7 has reached the position at the end of the track rails indicated in Fig. 9. In this position of the parts, the truck 7 is next made stationary, as for instance by the use of one or more suitable jacks 24. Then, through a reversal of the flexible connection 20 so that the same extends back beneath the machine and around the other idler 22 and the sprocket 13, the bar 2 is swung downward from the position shown in Fig. 9 to the position shown in Fig. 10 to cut its swinging or vertical cut extending in the form of an arc from the top of the entry to the bottom thereof. As soon as this cut is completed, the braking mechanism is preferably released and thereafter, through the connection of the clutch 11 and the reversal of the driving sprocket 13, the machine is propelled backward while the cutter chain 3 is operating, from the position shown in Fig. 10 to the position shown in Fig. 11, in such a manner as to make its withdrawal cut in which it cuts out the remainder of the vertical kerf. Obviously, if desired, however, instead of using the truck driving mechanism as above described in order thus to propel the machine toward or from the face in making its starting or withdrawal cuts, the flexible connection 20 may be utilized, the same then being connected in a well known manner, as shown in full lines in Fig. 12, to a point in advance of the machine and adjacent the face during the starting cut or, as shown in dotted lines in that figure, to a point in rear of the machine during the withdrawal cut.

During the use of my improved construction and while the cutter bar is cutting its vertical kerf in the face of the entry, certain impurities may be encountered, and I have accordingly provided improved means whereby an operator may cut around the same. These means preferably, as shown herein, include the turntable mounting 5 of the machine upon the truck, and preferably also comprise the guiding and supporting means 6 disposed beneath the front end of the machine in an arc preferably struck from the same center as the machine pivot, and cooperating means of suitable form whereby the machine may be adjusted about its pivot during cutting. As illustrated, these cooperating means assume the form of a double acting jack having its elements 25 and 26 pivotally connected to the machine and truck, respectively, at 27 and 28, and operatively connected by a reversely threaded turnbuckle 29. Thus, it will be observed that by adjusting the turnbuckle 29, the angle of the machine relative to the truck and the lateral position of the bar during its cut, may be regulated as desired. For example, referring to Fig. 4, it will be noted that the

normal kerf cut by the bar is illustrated as disposed between the lines A—A and extending vertically from the top of the entry to the bottom thereof, while the cut obtainable through adjustment of the turnbuckle 29 is illustrated as between the lines B—B, thereby clearly enabling an operator to cut around an impurity extending into the space between the left hand lines A and 10 B. Obviously, however, through the use of my improved mechanism, the operator may also remove impurities by utilization of these means or the means for angling the bar relative to the machine, or by the use 15 of either of these means in conjunction with the means for propelling the truck back and forth. For example, should an impurity be encountered during the starting cut, the same may readily be removed by withdrawing 20 the bar and inserting the same directly into the coal while in its transport position illustrated in full lines in Fig. 1, thereby weakening the coal beneath the impurity in such a manner as to enable the bar when 25 again inserted above the same to more readily tear out the obstruction. Conversely, the same method of procedure may be followed when an impurity is encountered when making the withdrawal cut, or, if desired, when 30 making that cut the bar may be returned to transport position and withdrawn and inserted when disposed at an angle, as during the starting cut, in such a manner as to tear away the coal on the opposite side of the 35 obstruction and thus permit the same to be more readily removed. If desired, the bar may also be inserted at other angles by providing any desired number of perforations 18 adapted to receive the pin 19. In the use 40 of my improvement, it will also be evident that through the provision of the turntable 5 the machine may swing into a variety of different angular positions to enable it to make swinging cuts at different angles, and 45 readily be locked in its different positions, by simply providing a series of perforations 31 in said turntable and a pin 32 adapted to be received in any one of the same and a suitable corresponding perforation, or perforations, in the truck frame 7.

In Fig. 6 I have illustrated a modified form of the construction shown in the remaining figures of the drawing. In this construction, it will be noted that the mining machine 1 is of the so-called room and pillar type and has its cutter bar 2 rigidly connected thereto as distinguished from pivotally connected thereto, as in a machine of the longwall type. Here the mining machine 1 is likewise disposed edgewise or on its side and itself pivoted upon a suitable pivot 33 disposed at a point adjacent the center of gravity of the machine and supported on suitable spaced upstanding oppositely located supports 34 carried on the 55 truck 7, and preferably swiveled thereon on a suitable swivel connection 35. In this construction, it will be observed that in addition to the feed sprocket 13 and the idlers 22, other cooperating idler sprockets 36, 37, 70 and 38 are provided which are adapted to receive the flexible feeding element 20 in different angular positions of the machine determined by the location of one or more pins 39 in suitable registering apertures 40 in the supports 34 and the machine frame. In this construction, as in the preceding construction, the machine may be transported from place to place when its bar is in a horizontal transport position corresponding 75 to that shown in Fig. 1. However, in this construction, when it is desired to adjust the bar from this position into its various operative positions, it will be observed that this is accomplished by threading the flexible feeding element 20 in different relations and attaching the end of the same to a suitable support or hook 41 disposable at different points in the face or longitudinally of the entry. For instance, in first swinging 80 the bar up to the position shown in Fig. 6, the chain is preferably extended around under the sprocket 13 and over the upper idler 22 and then downward over the idler 38 to the member 41, which is then disposed adjacent 85 the bottom and in rear of the machine. During the starting cut, the entire mechanism may obviously be propelled longitudinally toward the face by arranging the parts as shown. To swing the bar downward 90 in making its swinging cut, the chain may, obviously, also be passed over the lower idler 22 and the idler 37 to the member 41 which is then disposed adjacent 95 the bottom and in rear of the machine. During the starting cut, the entire mechanism may obviously be propelled longitudinally 100 toward the face by arranging the parts as shown. To swing the bar downward in making its swinging cut, the chain may, obviously, also be passed over the lower idler 22 and the idler 37 to the member 41 which is then disposed substantially on the level of the bottom and in advance of the machine. Finally, in making the withdrawal cut, the chain may be passed around the lower idler 22 and the front idler 37 to the member 41 which is then disposed 105 substantially on the level of the bottom but in rear of the machine. In this construction, however, it will be observed that it is necessary to drill the bottom or face to receive the member 41, or to attach the same or the chain to a jack, and for this reason 110 the self-contained form of the invention first described is preferred. Obviously, in this modified construction, however, any suitable truck driving mechanism of the type hereinabove described may, if desired, be utilized to propel the truck about the mine or to propel the same during the reciprocating movements in its cutting operation and thus avoid the necessity for drilling the face or the bottom to receive the member 41 before 115 making these movements.

As a result of my improvement, and particularly of the preferred form of the same, it will be observed that it is possible to advance the entry very rapidly, the machine 120 125 130

being adapted to rapid transport from place to place, and during the cutting operation being adapted to be operated under power with great facility in its movement from one cutting position to another, all of the mechanism, in the preferred form of my invention, being self-contained and requiring only relatively simple adjustments. It will also be observed that during the actual operation 10 of cutting a kerf the area of the kerf in an entry of a given size is materially reduced as compared with the area of the kerf required to be cut by an undercutter or any machine in which the cutting element moves 15 transversely of the entry. Attention is also directed to the fact that through the use of my improved construction it is possible to shoot the coal clear from the mine bottom so that the loader may work directly upon the 20 mine bottom without the necessity for digging up any unshot coal therefrom in a separate operation as is required when the kerf is inserted transversely at a point above the mine bottom and the shots are placed in the 25 coal above the kerf as ordinarily occurs with a transverse kerf cutter operating above the mine bottom. As a result of my improved construction it will also be observed that it is possible to utilize standard mining machines of either the longwall or room and 30 pillar type as shearing machines, without materially changing the machine or in any way destroying its efficiency in its original capacity, standard machines as a result of 35 my improvement being readily adapted to use in this connection and to use thereafter as bottom cutters when desired. These and other advantages of my improved construction will, however, be clearly apparent to 40 those skilled in the art.

While I have in this application specifically described two embodiments which my invention may assume in practice, it will be understood that these forms of the same are 45 used for purposes of illustration and that the invention may be modified and embodied in various other forms without departing from its spirit or the scope of the appended claims.

50 What I claim as new and desire to secure by Letters Patent is:

1. In a mining machine, a wheeled truck, cutting mechanism thereon including a cutter bar having cutting elements circulating in a vertical plane pivoted directly on a horizontal pivot at the front end of said truck, feeding mechanism operatively connected with said bar for swinging the same about its pivot, and truck driving mechanism co-operating with said truck wheels and operatively connectable with said feeding mechanism for moving said truck in either direction.

65 2. In a mining mechanism, in combination, a machine having a cutter bar provided

with elements moving in an orbit having major and minor axes and provided with means for driving said cutting elements and for moving said machine over the mine bottom during cutting operation, said machine being operative to slide on the bottom with the orbit of its cutting elements parallel to a horizontal plane, and a mounting for said machine comprising a portable member and means thereon for supporting said machine with the orbit of its cutting elements parallel to a vertical plane, said mechanism including means whereby said bar may be moved towards and from a working face while maintaining a uniform angle relative thereto or may be caused to move while said machine remains stationary in such manner that its major axis may traverse an angle such that in its extreme positions it will occupy positions respectively above and below a horizontal line which is in the plane of the angle and passes through its vertex.

3. In a mining machine, a truck, a self-propelled machine disposed edgewise thereon including a forwardly extending cutter bar having cutting elements which circulate parallel to a vertical plane about the periphery thereof and pivoted on a horizontal pivot at the front end of said truck, feeding mechanism operatively connected with said bar for swinging the same about its pivot, and truck wheel driving mechanism operatively connectable with said feeding mechanism for moving said truck in different directions.

4. In an entry driving machine, a wheeled truck, a self-propelled mining machine disposed edgewise on said truck including a pivoted plane forwardly extending cutter bar movable about a horizontal pivot at the front end of said truck, means for swinging said bar in a vertical plane about its pivot, and means for moving said truck in different directions, each of said last mentioned means being operatively connected to the same source of power.

5. In a mining machine, a truck, a self-propelled mining machine disposed edgewise thereon including a cutter bar provided with cutting elements circulating in a plane orbit and pivoted on a horizontal pivot at the front end of said truck, feeding mechanism operatively connected with said bar for swinging the same about its pivot, and truck wheel driving mechanism operatively connectable with said feeding mechanism for feeding said truck in either direction to feed the bar into the work or to withdraw the same.

6. In an entry driving machine, a wheeled truck, a self-propelled mining machine disposed edgewise on said truck including a pivoted flat cutter bar movable about a horizontal pivot at the front end of said truck, means for swinging said bar in a vertical

- plane about its pivot, and means for feeding said truck in either direction to feed the bar into the work or to withdraw the same, each of said last mentioned means 5 being operatively connected to the same source of power.
7. In an entry driving machine, a truck, a self-propelled mining machine supported edgewise thereon including a flat cutter bar pivoted on a horizontal pivot at the front end of said truck, feeding mechanism operatively connected with said bar for swinging the same about its pivot, means for swinging said cutting mechanism across the face of 10 the entry, and truck wheel driving mechanism operatively connectable with said feeding mechanism for moving said truck in either direction.
8. In an entry driving machine, a wheeled truck, a self-propelled mining machine disposed edgewise on said truck including a pivoted flat cutter bar movable about a horizontal pivot at the front end of said truck, means for swinging said bar in a vertical 15 plane about its pivot, means for swinging said cutting mechanism across the face of the entry, and means for moving said truck in either direction, each of said last mentioned means being operatively connected to 20 the same source of power.
9. In a mining machine, a truck movable over a trackway, a self-propelled mining machine disposed edgewise thereon including a plane forwardly extending cutter bar, means forming a pivot for said bar supported by said truck and located above the latter, and means for swinging said bar about its pivot to insert a vertical kerf in an upstanding face which is perpendicular 25 to the line of the trackway.
10. In a mining machine, a truck movable over a trackway, a self-propelled mining machine supported edgewise thereon including a flat forwardly extending cutter bar, means forming a pivot for said bar supported by said truck and located above the latter, and feeding means operatively connected to said machine for moving said bar bodily and also about its pivot to insert a 30 vertical kerf in an upstanding face which is perpendicular to the line of the trackway.
11. In a mining machine, a truck movable over a trackway, a self-propelled mining machine supported edgewise thereon including a flat forwardly extending cutter bar, means forming a pivot for said bar supported by said truck and located above the latter, means for swinging said bar about its pivot to insert a vertical kerf in an upstanding face which is perpendicular to the line of the trackway, and a swivel mounting interposed between said machine and said truck.
12. In a mining machine, a truck movable over a trackway, a self-propelled mining 35 machine supported edgewise thereon including a plane forwardly extending cutter bar, means forming a pivot for said bar supported by said truck and located above the latter, means for swinging said bar about its pivot to insert a vertical kerf in an upstanding face which is perpendicular to the line of the trackway, and truck driving mechanism operatively connectable with said feeding mechanism for moving said truck in either direction.
13. In a mining machine, a wheeled truck movable over a trackway, a mining machine supported edgewise thereon and comprising feeding and cutting mechanism, the latter including a forwardly extending cutter bar, means supported by said truck and forming a transversely disposed pivot relative to which said bar is movable in a vertical plane, and means connectable to said feeding mechanism for selectively moving said bar about its pivot or bodily therewith relative to a face.
14. In a mining machine, a wheeled truck movable over a trackway, a mining machine supported edgewise thereon and comprising feeding and cutting mechanism, the latter including a forwardly extending cutter bar, means swiveled on said truck and forming a transversely disposed pivot relative to which said bar is movable in a vertical plane, and means including operative connections to said feed mechanism for selectively moving said bar about its pivot or bodily with the latter relative to said trackway.
15. In a mining machine, a wheeled truck movable over a trackway, a mining machine supported edgewise thereon and comprising feeding and cutting mechanism, the latter including a forwardly extending cutter bar, means supported by said truck and forming a transversely disposed pivot relative to which said bar is movable in a vertical plane, operative connections for moving said bar about its pivot, and truck wheel driving mechanism for moving said pivot relative to said trackway.
16. In a mining machine, a wheeled truck movable over a trackway, a unitary mining machine supported edgewise thereon comprising feeding and cutting mechanism, the former including means for effecting bodily feeding movement of the machine during cutting and the latter including a forwardly extending cutter bar, means supported by said truck forming a cutter bar pivot relative to which said bar is movable, and means for moving said bar relative to an upstanding face to insert a vertical kerf therein.
17. In a mining apparatus, a wheeled truck, cutting mechanism thereon including a cutter bar pivotally mounted on said truck, means on said truck for effecting swinging of said bar about its pivot including a rotatable member adapted to cooperate directly with flexible means connectible to swing 120 125 130

the bar, and truck wheel driving mechanism including a driving element coaxial with said rotatable member and connectible to the latter to effect truck propulsion.

- 5 18. In a mining apparatus, a wheeled truck, cutting mechanism thereon including a cutter bar pivotally mounted on said truck for swinging in a vertical plane, means on said truck for effecting swinging of said bar about its pivot including a rotatable member adapted to cooperate directly with flexible means connectible to swing the bar, and truck wheel driving mechanism including a driving element coaxial with said rotatable member and connectible to the latter to effect truck propulsion.

- 10 19. In a mining apparatus, a wheeled truck, cutting mechanism thereon including a cutter bar pivotally mounted on said truck, means on said truck for effecting swinging of said bar about its pivot including a rotatable member adapted to cooperate directly with flexible means connectible to swing the bar, and truck wheel driving mechanism including a driving element coaxial with said rotatable member and connectible to the latter to effect truck propulsion.

- 15 20. In a mining apparatus, a wheeled truck, cutting mechanism thereon including a cutter bar pivotally mounted on said truck for swinging in a vertical plane, means on said truck for effecting swinging of said bar about its pivot including a rotatable member adapted to cooperate directly with flexible means connectible to swing the bar, and truck wheel driving mechanism including a driving element coaxial with said rotatable member and connectible to the latter to effect truck propulsion.

- 25 21. In a mining apparatus, a wheeled truck, cutting mechanism thereon including a cutter bar pivotally mounted on said truck, means on said truck for effecting swinging of said bar about its pivot including a rotatable member adapted to cooperate directly with flexible means connectible to swing the bar, and truck wheel driving mechanism including a driving element rotatable at equal angular rates with said rotatable member and operative on rotation to effect truck wheel drive.

- 30 22. In a mining apparatus, a wheeled truck, cutting mechanism thereon including a cutter bar pivotally mounted on said truck, means on said truck for effecting swinging of said bar about its pivot including a rotatable member adapted to cooperate directly with flexible means connectible to swing the bar, and truck wheel driving mechanism including a driving element rotatable at equal angular rates and in like directions with said rotatable member and operative on rotation to effect truck wheel drive.

- 35 23. In a mining apparatus, a wheeled

truck, cutting mechanism thereon including a cutter bar pivotally mounted on said truck, means on said truck for effecting swinging of said bar about its pivot including a rotatable member adapted to cooperate directly with flexible means connectible to swing the bar, and truck wheel driving mechanism including a driving element rotatable at equal angular rates with said rotatable member and flexible connections between said element and said truck wheels.

24. In a mining apparatus, a wheeled truck, cutting mechanism thereon including a cutter bar pivotally mounted on said truck, means on said truck for effecting swinging of said bar about its pivot including a rotatable member adapted to cooperate directly with flexible means connectible to swing the bar, and truck wheel driving mechanism including a driving element rotatable at equal angular rates and in like directions with said rotatable member and flexible connections between said element and said truck wheels.

25. In a mining apparatus, a wheeled truck, cutting mechanism including a cutter bar on said truck, means between said truck and bar whereby the latter can move to make a swinging cut, means on said truck for effecting such movement of said bar including a rotatable member adapted to cooperate directly with flexible means connectible to swing the bar, and truck wheel driving mechanism including a driving element coaxial with said rotatable member and connectible to the latter to effect truck propulsion.

26. In a mining apparatus, a wheeled truck, cutting mechanism including a cutter bar on said truck, means between said truck and bar whereby the latter can move to make a swinging cut in a vertical plane, means on said truck for effecting such movement of said bar including a rotatable member adapted to cooperate directly with flexible means connectible to swing the bar, and truck wheel driving mechanism including a driving element coaxial with said rotatable member and connectible to the latter to effect truck propulsion.

27. In a mining apparatus, a wheeled truck, cutting mechanism including a cutter bar on said truck, means between said truck and bar whereby the latter can move to make a swinging cut, means on said truck for effecting such movement of said bar including a rotatable member adapted to cooperate directly with flexible means connectible to swing the bar, and truck wheel driving mechanism including a driving element coaxial with said rotatable member and flexible connections between the same and said truck wheels.

28. In a mining apparatus, a wheeled truck, cutting mechanism including a cutter

- bar on said truck, means between said truck and bar whereby the latter can move to make a swinging cut in a vertical plane, means on said truck for effecting such movement of said bar including a rotatable member adapted to cooperate directly with flexible means connectible to swing the bar, and truck wheel driving mechanism including a driving element coaxial with said rotatable member and flexible connections between the same and said truck wheels. 5
29. In a mining apparatus, a wheeled truck, cutting mechanism including a cutter bar on said truck, means between said truck and bar whereby the latter can move to make a swinging cut, means on said truck for effecting such movement of said bar including a rotatable member adapted to cooperate directly with flexible means connectible to swing the bar, and truck wheel driving mechanism including a driving element rotatable at equal angular rates with said rotatable member and operative on rotation to effect truck wheel drive. 10
30. In a mining apparatus, a wheeled truck, cutting mechanism including a cutter bar on said truck, means between said truck and bar whereby the latter can move to make a swinging cut, means on said truck for effecting such movement of said bar including a rotatable member adapted to cooperate directly with flexible means connectible to swing the bar, and truck wheel driving mechanism including a driving element rotatable at equal angular rates and in like directions with said rotatable member and operative on rotation to effect truck wheel drive. 15
31. In a mining apparatus, a wheeled truck, cutting mechanism including a cutter bar on said truck, means between said truck and bar whereby the latter can move to make a swinging cut, means on said truck for effecting such movement of said bar including a rotatable member adapted to cooperate directly with flexible means connectible to swing the bar, and truck driving mechanism including a driving element rotatable at equal angular rates with said rotatable member and flexible connections between said member and said truck wheels. 20
32. In a mining apparatus, a wheeled truck, cutting mechanism including a cutter bar on said truck, means between said truck and bar whereby the latter can move to make a swinging cut, means on said truck for effecting such movement of said bar including a rotatable member adapted to cooperate directly with flexible means connectible to swing the bar, and truck driving mechanism including a driving element rotatable at equal angular rates and in like directions with said rotatable member and flexible connections between said member and said truck wheels. 25
33. In an entry driving machine, a member adapted for movement of translation relative to the mine bottom towards and from the face of the entry, cutting mechanism carried thereby comprising an elongated cutter bar having cutting elements traveling in an orbit parallel to a vertical plane which is parallel to the direction of translational movement of said member towards and from the face, said elements arranged to cut a kerf to admit said bar and being operative whether said bar is presented endwise or sidewise to the material to be cut, means including a horizontal pivot mounted on said member at a fixed distance from the mine bottom and disposed perpendicular to the plane of the orbit of said cutting elements for permitting said cutting mechanism to swing during cutting to make a vertical shearing cut, means for rigidly positioning said cutting mechanism relative to said member at a plurality of angles to a horizontal line parallel to the path of translatory movement of said member, and self-contained power operated means on said member for feeding the latter towards and away from the face during cutting, while the cutting elements travel in their orbits in one direction, and for swinging said bar by power. 30
34. In an entry driving machine, a member adapted for movement of translation relative to the mine bottom towards and from the face of the entry, cutting mechanism carried thereby comprising an elongated cutter bar having cutting elements traveling in an orbit parallel to a vertical plane which is parallel to the direction of translational movement of said member towards and from the face, said elements arranged to cut a kerf to admit said bar and being operative whether said bar is presented endwise or sidewise to the material to be cut, means including a horizontal pivot mounted on said member at a fixed distance from the mine bottom and disposed perpendicular to the plane of the orbit of said cutting elements for permitting said cutting mechanism to swing during cutting to make a vertical shearing cut, means for rigidly positioning said cutting mechanism relative to said member at a plurality of angles to a horizontal line parallel to the path of translatory movement of said member, and self-contained power operated means on said member for feeding the latter towards and away from the face during cutting while the cutting elements travel in their orbits in one direction, and for swinging said bar by power, including a driving member rotating oppositely during opposite feeding movements of said first mentioned member. 35
35. In an entry driving machine, a member adapted for movement of translation relative to the mine bottom towards and

from the face of the entry, cutting mechanism carried thereby comprising an elongated cutter bar having cutting elements traveling in an orbit parallel to a vertical plane which is parallel to the direction of translational movement of said member towards and from the face, said elements arranged to cut a kerf to admit said bar and being operative whether said bar is presented endwise or sidewise to the material to be cut, means including a horizontal pivot mounted on said member at a fixed distance from the mine bottom and disposed perpendicular to the plane of the orbit of said cutting elements for permitting said cutting mechanism to swing during cutting to make a vertical shearing cut, means for moving said cutting mechanism into and locking it in a plurality of different angular relations to a horizontal line parallel to the path of translatory movement of said member including a rotating element, and self-contained power operated means on said member for feeding the latter towards and away from the face during cutting while the cutting elements travel in their orbits in one direction including a driving member rotating oppositely during opposite feeding movements of said member and coaxial with said element.

36. In an entry driving machine, a member adapted for movement of translation relative to the mine bottom towards and from the face of the entry, cutting mechanism carried thereby comprising an elongated cutter bar having cutting elements traveling in an orbit parallel to a vertical plane which is parallel to the direction of translational movement of said member towards and from the face, said elements arranged to cut a kerf to admit said bar and being operative whether said bar is presented endwise or sidewise to the material to be cut, means including a horizontal pivot mounted on said member at a fixed distance from the mine bottom and disposed perpendicular to the plane of the orbit of said cutting elements for permitting said cutting mechanism to swing during cutting to make a vertical shearing cut, means for rigidly positioning said cutting mechanism relative to said member at a plurality of angles to a horizontal line parallel to the path of translatory movement of said member, and self-contained power operated means on said member for feeding the latter towards and away from the face during cutting while the cutting elements travel in their orbits in one direction including a driving member rotating oppositely during opposite feeding movements of said member and rotating rail engaging traction means driven by said driving member.

37. In a mining machine, a wheeled truck, cutting mechanism on said truck including a

pivoted plane cutter carrying cutter bar pivoted directly on a horizontal pivot at the front end of said truck, means for swinging said bar in a vertical plane about its pivot, and power operated truck wheel driving means for moving said truck by the traction of said truck wheels in either direction during cutting while the cutters on said bar move in one direction only.

38. In a mining machine, a wheeled truck movable over a trackway, mining machine mechanisms supported thereon comprising feeding and cutting mechanism, the latter including a forwardly extending cutter bar provided with cutting elements arranged to cut a kerf to admit said bar, means supported by said truck forming a transversely disposed pivot relative to which said bar is movable edgewise in a vertical plane, flexible means for swinging said bar relative to an upstanding face to insert a vertical kerf therein, a swivel mounting disposed between said bar pivot and truck, and means for adjusting said bar pivot angularly thereon relative to said truck.

39. In a mining apparatus, a wheeled supporting member movable along a trackway, cutting mechanism thereon including an elongated cutter bar having orbitally moving cutting elements arranged to cut a kerf to admit said bar and swingable relative to a fixed axis to make a swinging cut in a vertical plane, power means for effecting downward swinging of said cutting mechanism during cutting, and means operative to effect opposite longitudinal movements of said supporting member during cutting and at a cutting speed without reversal of the orbital movement of said cutting elements including a driving member rotatable in opposite directions by an element of said power means.

40. In a mining apparatus, a wheeled supporting member movable along a trackway, cutting mechanism thereon including an elongated cutter bar having orbitally moving cutting elements arranged to cut a kerf to admit said bar and swingable relative to a fixed axis to make a swinging cut in a vertical plane, power means for effecting downward swinging of said cutting mechanism during cutting, and means operative to effect opposite longitudinal movements of said supporting member during cutting and at a cutting speed without reversal of the orbital movement of said cutting elements including a driving member rotatable at like speeds in opposite directions by an element of said power means.

41. In a mining apparatus, a wheeled truck, a mining machine thereon comprising cutting mechanism, actuating means therefore, means for moving said cutting mechanism during cutting including a rotatable element adapted to cooperate directly with flexible feeding means in effecting movement

of said cutting mechanism, and truck wheel driving mechanism including a rotatable element coaxial with said first mentioned rotatable element and operable independently 5 of said cutting mechanism.

42. In a mining apparatus, a wheeled truck, a mining machine thereon comprising cutting mechanism, actuating means therefor, means for moving said cutting mechanism during cutting including a rotatable element adapted to cooperate directly with flexible feeding means in effecting movement of said cutting mechanism, and truck wheel driving mechanism operative to force said 10 bar to a position substantially fully in the coal and including a rotatable element coaxial with said first mentioned rotatable element, each of said elements rotating on a horizontal axis.

43. In a mining apparatus, a wheeled truck, a mining machine thereon comprising cutting mechanism, actuating means therefor, means for moving said cutting mechanism during cutting including a rotatable element adapted to cooperate directly with flexible feeding means in effecting movement 25 of said cutting mechanism, and truck wheel driving mechanism operative to force said bar to a position substantially fully in the 30 coal and including a rotatable element rotatable at an equiangular rate with said first mentioned rotatable element.

44. In a mining apparatus, a wheeled truck, a mining machine thereon comprising cutting mechanism, actuating means therefor, means for moving said cutting mechanism during cutting including a rotatable element adapted to cooperate directly with flexible feeding means in effecting movement 35 of said cutting mechanism, and truck wheel driving mechanism operative to force said bar to a position substantially fully in the coal and including a rotatable element rotatable at an equiangular rate with said first 40 mentioned rotatable element, each of said elements rotating on a transverse axis.

45. In a mining apparatus, a wheeled truck, a frame thereon, cutting mechanism on said frame, means on said frame for effecting movement of said cutting mechanism during cutting and including a rotatable feed operating member rotating on a transversely extending axis, a rotatable truck wheel driving member arranged coaxially with said feed operating member, and means whereby said members may be rotated together, or one by itself, at a cutting speed.

46. In a mining apparatus, a wheeled truck, a frame thereon, cutting mechanism on said frame, means on said frame for effecting movement of said cutting mechanism during cutting and including a rotatable feed operating member rotating on a transversely extending axis, a rotatable 60 truck wheel driving member arranged coaxially with said feed operating member, and means whereby said members may be rotated together, or one by itself.

47. In a mining apparatus, a wheeled truck, a frame thereon, cutting mechanism on said frame, means on said frame for effecting movement of said cutting mechanism during cutting and including a rotatable feed operating member adapted to cooperate 70 directly with flexible feeding means rotating on a transversely extending axis, a rotatable truck wheel driving member arranged coaxially with said feed operating member, and means whereby said members may be rotated 75 together, or one by itself.

48. In a mining apparatus, a wheeled truck, a frame thereon, cutting mechanism on said frame, means on said frame for effecting movement of said cutting mechanism during cutting and including a rotatable feed operating member adapted to cooperate 85 directly with flexible feeding means rotating on a transversely extending axis, a rotatable truck wheel driving member arranged coaxially with said feed operating member, and means for independently controlling one of 90 said members.

49. In a mining apparatus, a wheeled truck movable on a trackway, cutter mechanism thereon comprising a motor and a pivotally mounted cutter chain carrying cutter bar adapted to swing in a vertical plane at the end of the truck, mechanism solely supported by said truck for swinging said 95 bar in either direction by power in the manner described, and power operated means solely supported by said truck for feeding said bar and truck longitudinally of the trackway in opposite directions during cutting at cutting speeds and without reversal 100 of the cutter mechanism.

50. In a mining apparatus, a wheeled truck movable on a trackway, cutter mechanism thereon comprising a motor and a pivotally mounted cutter chain carrying cutter bar adapted to swing in a vertical plane at the end of the truck, mechanism solely supported by said truck for swinging said bar 110 by power in the manner described, and power operated means solely supported by said truck and actuated by said motor for feeding said bar and truck longitudinally of the trackway in opposite directions during cutting at cutting speeds and without reversal 115 of the cutter mechanism.

51. In a mining apparatus, a wheeled truck movable on a trackway, cutter mechanism including a cutter bar disposable in fixed relation at acute angles to the trackway and pivotally mounted on said truck, and self-contained power operated means supported on said truck for actuating the wheels of the latter to move the bar rectilinearly of the trackway when said bar is 120 125 130

disposed at an angle to the direction thereof in a vertical plane, for moving said bar relatively transversely in said plane, and for actuating the wheels of said truck in the opposite direction, to form a vertical parallel ribbed kerf of a depth substantially equal to the length of the bar and in a face in front of the end of the trackway.

52. In a mining apparatus, a wheeled truck movable on a trackway, cutter mechanism including a cutter bar disposable in fixed relation at acute angles to the trackway and pivotally mounted on said truck, and self-contained power operated means comprising but a single motor supported on said truck for actuating the wheels of the latter to move the bar rectilinearly of the trackway when said bar is disposed at an angle to the direction thereof in a vertical plane, for moving said bar relatively transversely in said plane, and for actuating the wheels of said truck in the opposite direction, to form a vertical parallel ribbed kerf of a depth substantially equal to the length of the bar and in a face in front of the end of the trackway.

53. In a mining apparatus, supporting means movable on a trackway, cutter mechanism thereon comprising a pivotally mounted cutter bar having a chain adapted to cut a vertical kerf for said bar in a face when said bar is presented edgewise thereto, and self-contained power operated means for moving said bar bodily rectilinearly of the trackway, about its pivot in the same plane, and reversely rectilinearly of the trackway to insert a parallel ribbed kerf in a face in front of the end of the trackway, said self-contained power operated means comprising wheels engageable with said trackway and oppositely actuatable to effect such opposite bodily rectilinear movements of said bar.

54. In a mining apparatus, supporting means movable on a trackway, cutter mechanism thereon comprising a pivotally mounted cutter bar having a chain adapted to cut a vertical kerf for said bar in a face when said bar is presented edgewise thereto, and self-contained power operated means comprising but a single motor for moving said bar bodily rectilinearly of the trackway, about its pivot in the same plane, and reversely rectilinearly of the trackway to insert a parallel ribbed vertical kerf in a face in front of the end of the trackway, said self-contained power operated means comprising wheels engageable with said trackway and oppositely actuatable to effect such opposite bodily rectilinear movements of said bar.

55. In a mining apparatus, a wheeled truck movable on a trackway, cutter mechanism thereon comprising a motor and a pivotally mounted cutter chain carrying cutter bar swingable in a vertical plane at the end of the truck, and self-contained power op-

erated mechanism supported solely by said truck for moving said bar angularly in its vertical plane, and for actuating said truck wheels to effect reverse longitudinal bodily movements of said bar relative to said trackway during cutting.

56. In a mining apparatus, a wheeled truck movable over a trackway, a mining machine supported thereon in edgewise relation thereto, and comprising cutting mechanism including a normally forwardly extending cutter bar movable in a vertical plane about a transversely disposed pivot, said mining machine also comprising feeding mechanism, and means connectible to said feeding mechanism for selectively moving said bar during cutting about said pivot or bodily therewith relative to a face to insert a kerf in a face extending transversely of the trackway.

57. In a mining apparatus, a wheeled truck movable over a trackway, a mining machine supported thereon in edgewise relation thereto, and comprising cutting mechanism including a normally forwardly extending cutter bar movable in a vertical plane about a transversely disposed pivot, said mining machine also comprising feeding mechanism, and means connectible to said feeding mechanism for selectively moving said bar during cutting about said pivot or bodily therewith relative to a face to insert a kerf in a face extending transversely of the trackway, said last mentioned means including truck wheel driving mechanism.

58. In a mining apparatus, a wheeled truck movable over a trackway, a mining machine supported thereon in edgewise relation thereto, and comprising cutting mechanism including a normally forwardly extending cutter bar movable in a vertical plane about a transversely disposed pivot, said mining machine also comprising feeding mechanism, and means connectible to said feeding mechanism for selectively moving said bar during cutting about said pivot or bodily therewith relative to a face to insert a kerf in a face extending transversely of the trackway, said last mentioned means including truck wheel driving mechanism operatively connected with said feeding mechanism.

59. In a mining machine, a wheeled support, a machine frame thereon including a motor, cutting mechanism at one end of said motor including a swingable cutter bar disposed in a vertical plane, and means for operating said cutting mechanism and swinging said bar respectively connected to opposite ends of said motor.

60. In a mining machine, a wheeled support, a machine frame thereon including a motor, cutting and feeding mechanisms connected to opposite ends thereof, said cutting mechanism being adjustable and disposed in

a vertical plane, and means for adjusting said cutting mechanism driven by said feeding mechanism.

61. In a mining machine, a wheeled support, a machine frame thereon including a motor, cutting and feeding mechanisms connected to opposite ends thereof, said cutting mechanism being adjustable and disposed in a vertical plane, and means for adjusting 10 said cutting mechanism connectible at will with said feeding mechanism.

62. In a mining machine, a wheeled support, a machine frame thereon including a motor, cutting and feeding mechanisms at 15 opposite ends thereof, cutter adjusting mechanism for adjusting said cutting mechanism in a vertical plane, and means for actuating one of said mechanisms from the front end of the motor and the remainder from the 20 rear end of the motor.

63. In a mining machine, a wheeled support, a machine frame thereon movable rectilinearly during cutting and including a motor having an axis of rotation parallel to 25 the direction of rectilinear movement and a driving gear element at each end thereof, cutting mechanism including a cutter bar adjustable on an axis on the front end of said frame, means for driving said cutting mechanism from one end of said motor, and means for adjusting the bar about its axis driven from the opposite end of said motor.

64. In a mining machine, a wheeled support, a machine frame thereon including a 35 motor, cutting mechanism including a cutter bar adjustable on a horizontal transverse axis on the front end of said frame, means for driving said cutting mechanism from one end of said motor, and means for adjusting the bar about its axis driven from the opposite 40 site end of said motor.

65. In a mining machine, a machine frame including a motor having a driving gear element at each end thereof, cutting mechanism 45 including a cutter bar adjustable on an axis on the front end of said frame, means for driving said cutting mechanism from one end of said motor, means for adjusting the bar about its axis driven from the opposite 50 end of said motor, and feeding mechanism for said frame operative to feed the same rectilinearly in opposite directions towards and from a face during cutting and driven from the last mentioned end of said motor 55 and driven from said adjusting means.

66. In a mining machine, a machine frame including a motor, cutting mechanism including a cutter bar adjustable on a horizontal transverse axis on the front end of 60 said frame, means for driving said cutting mechanism from one end of said motor, means for adjusting the bar about its axis driven from the opposite end of said motor, and feeding mechanism for said frame 65 driven from the last mentioned end of said

motor and driven from said adjusting means.

67. In a mining machine, a wheeled support, a machine frame thereon including a motor, cutting mechanism at one end of said 70 motor including a swinging cutter bar disposed in a vertical plane, and means for operating said cutting mechanism and reversely swinging said bar respectively connected to opposite ends of said motor. 75

68. In a mining machine, a machine frame including a motor, cutting and cutter adjusting mechanisms supported on said frame, operative connections between one end of said motor and said cutting mechanism, 80 operative connections between the other end of said motor and said cutter adjusting mechanism, said cutting mechanism being adjustable and disposed in a vertical plane, and means for feeding said cutting mechanism driven from said operative connections between said cutter adjusting mechanism and said motor. 85

69. In a mining machine adapted to arc-wall cutting, a wheeled truck, a shearing cutter chain carrying cutter bar thereon, a cutter chain driving sprocket coaxial with the pivot of said bar, a bar swinging member movable about said bar pivot, a horizontal motor having its longitudinal axis extending 90 longitudinally of the truck, and operative connections between one end of said motor and said sprocket and between the other end of said motor and said member. 95

70. In a mining machine, a wheeled truck, 100 a machine frame thereon, a motor thereon having a power shaft extending longitudinally of said frame, a cutter chain carrying cutter bar swingable about a horizontal transverse axis at one end of said motor, 105 motor operated cutter chain driving means, and means driven by the end of said power shaft remote from said cutter bar for adjusting the latter oppositely about its axis.

71. In a mining machine, a wheeled truck, 110 a machine frame thereon including a motor having a driving gear element at each end thereof, cutting mechanism including a cutter bar carrying orbitally moving cutting elements and adjustable on an axis on the 115 front end of said frame, means for driving said cutting mechanism from one end of said motor, and means for adjusting said bar about its axis and effecting opposite rectilinear feeds thereof while said elements 120 traverse at all times their orbits in the same direction, said last mentioned means driven from the opposite end of said motor.

72. In a mining machine, a wheeled truck, 125 a machine frame thereon including a motor, cutting mechanism including a cutter bar carrying orbitally moving cutting elements and adjustable on a transverse axis on the front end of said frame to make a shearing cut, means for driving said cutting mecha- 130

nism from one end of said motor, and means for adjusting said bar about its axis and effecting opposite rectilinear feeds thereof while said elements traverse at all times their orbits in the same direction, said last mentioned means driven from the opposite end of said motor.

73. In a mining machine, a wheeled truck, a machine frame thereon including a motor, cutting mechanism including a cutter bar carrying orbitally moving cutting elements and adjustable on an axis on the front end of said frame, means for driving said cutting mechanism from one end of said motor, and means for adjusting said bar about its axis and effecting opposite rectilinear feeds thereof while said elements traverse at all times their orbits in the same direction, said last mentioned means driven from the opposite end of said motor and including a flexible element and rotatable means cooperating therewith.

74. In a mining machine, a wheeled truck, a machine frame thereon including a motor, cutting mechanism including a cutter bar carrying orbitally moving cutting elements and adjustable on a transverse axis on the front end of said frame, means for driving said cutting mechanism from one end of said motor, and means for adjusting said bar about its axis and effecting opposite rectilinear feeds thereof while said elements traverse at all times their orbits in the same direction, said last mentioned means driven from the opposite end of said motor and including a flexible element and rotatable means cooperating therewith.

75. In a mining machine, a wheeled truck, a motor having a rotating shaft, a frame mounted on said truck and supporting said motor, a vertically swinging cutting mechanism at one end of and actuated by such end of said motor, and means for effecting opposite rectilinear bodily movements of said cutting mechanism and opposite swinging movements of said bar actuated by the opposite end of said motor and including a flexible chain member.

76. In a mining machine, a wheeled truck, a body thereon, a horizontal motor carried by said body and having its longitudinal axis extending lengthwise of said truck, cutting mechanism driven from the forward end of said motor including a cutter bar pivoted on a transverse axis at the front end of said body for vertical swinging movement, mechanism driven from the rear end of said motor for swinging said cutter bar about its

60 pivot to effect a swinging cut, and mechanism driven from the rear end of said motor for bodily feeding said machine in opposite directions for effecting sumping and withdrawal cuts.

77. In a mining machine, a wheeled truck, a body thereon, a horizontal motor carried by said body and having its longitudinal axis extending lengthwise of said truck, cutting mechanism driven from the forward end of said motor including a cutter bar pivoted on a transverse axis at the front end of said body for vertical swinging movement, mechanism driven from the rear end of said motor for swinging said cutter bar about its pivot to effect a swinging cut and mechanism driven from the rear of said motor and connected to the truck wheels for driving the latter for bodily feeding the machine in opposite directions to effect sumping and withdrawal cuts.

78. In a mining machine, a wheeled truck, a self propelled mining machine disposed edgewise thereon including a cutter bar provided with cutting elements circulating in a plane orbit pivoted on a horizontal pivot at the front end of said truck and including a motor, feeding mechanism driven from one end of said motor operatively connected with said bar for swinging the same about its pivot, truck driving mechanism driven from the same end of said motor operatively connected with said feeding mechanism for feeding said truck in either direction to feed said bar into the work or to withdraw the same, and mechanism driven from the opposite end of said motor for actuating said cutting elements.

79. In a mining machine, a wheeled truck, cutting mechanism thereon including a cutter bar having cutting elements circulating in a vertical plane and pivoted directly on a horizontal pivot at the front end of said truck and including a motor, feeding mechanism driven from the rear end of said motor operatively connected with said bar for swinging the same about its pivot, truck driving mechanism cooperating with said truck wheels and operatively connectible with said feeding mechanism for moving said truck in either direction said truck driving mechanism being driven from the rear end of said motor and mechanism driven from the front end of said motor, for actuating said cutting elements.

In testimony whereof I affix my signature.

CHARLES BRAND OFFICER.
